UNITED STATES PATENT OFFICE

HENRY L. GUENTHER, OF LOS ANGELES, CALIFORNIA

DOUBLE-SEAMING MACHINE

Application filed August 22, 1928. Serial No. 301,318.

This invention relates to can making and closing machinery, and particularly pertains to a double seaming machine.

In the canning industry there is at the present time a demand for a double seaming machine to be used in closing sanitary cans and which machine will be of a few simple parts and may be easily operated at a relatively high speed without probability of spilling the contents of the cans as they are fed into and through the machine. With this in view, it has been the principal object of the present invention to provide a can double seaming machine which is of simple design and construction and occupies a relatively small floor space and will act effectively to rapidly form a lock seam between a can body and its cap.

The present invention contemplates the provision of a can double seaming machine of the intermittent motion type, being formed with means for initially curling the same while the can stands stationary and thereafter spin the can at rapid speed to finally form and close the seam.

The invention is illustrated by way of example in the accompanying drawings, in which:

Fig. 1 is a view in plan showing the complete machine with which the present invention is concerned, and including the can and cap feed mechanisms.

Fig. 2 is a view in vertical section through the machine as seen on the line 2—2 of Fig. 1, and particularly discloses the first seaming operation mechanism.

Fig. 3 is a view in vertical section through the machine as seen on the line 3—3 of Figs. 1 and 2, and particularly discloses the two seaming stations with relation to the cap feed.

Fig. 4 is a view in horizontal section through the body of the seaming mechanism as seen on the line 4—4 of Figs. 2 and 3, showing the relation of the two seaming stations to each other.

Fig. 5 is a fragmentary view in plan showing the driving clutch and brake arrangement.

Referring more particularly to the drawings, 10 indicates a bed plate having a hori-

zontal upper floor 11 and vertical side walls whereby a housing 12 will be provided within which the driving gear trains of the machine may be enclosed. Suitable cover boards 13 are mounted over openings in the end walls of the bed plate and when moved permit access to said gear trains.

Supported upon the bed plate 10 adjacent one end thereof is a column 14 which serves as a support. At its upper end is a bearing structure 15 which overhangs the column and the bed plate to provide a substantially C-shaped frame for the entire double seaming machine. The overhead bearing structure 15 carries bearings 16 and 17, to receive a horizontally extending driving mandrel 18, one end of this mandrel is provided with a hand wheel 19 by which it may be manually rotated. The opposite end of the mandrel as more clearly shown in Fig. 5 of the drawings is provided with a driving pulley 20 around which a belt 21 is rove. A clutch structure 22 is secured in operative relation to the mandrel 18 and the pulley 20, so that driving connection between the pulley and the mandrel may be directed at the will of the operator. This clutch structure embodies an operating finger 23, as one of its elements. The finger extends outwardly and engages the tapered face of operating cone 24, which may be shifted longitudinally upon the shaft 18 to establish or discontinue the clutch operation. The operating cone 24 is pivoted by trunnions 25 to shift yoke 26 which forms part of a bell crank 27. The opposite arm 28 of the bell crank 27 carries a brake shoe 29 which may be brought to bear against a brake drum 30, mounted on the mandrel 18. The bell crank is mounted upon a pivot pin 31 and is operated by a clutch lever 32 which may be swung horizontally to oscillate the bell crank and alternately actuate the clutch and the brake.

The mandrel 18 carries a bevel gear 33 which is in mesh with a bevel pinion 34. This pinion is secured to the upper end of a seaming drive shaft 35. This shaft extends vertically and is rotatably supported in a bearing 36 carried by a cantilever arm 38 secured to the column 14 near the upper end 100

thereof. The lower end of the seaming shaft 35 is rotatably supported in a bearing 39 formed as a part of the floor 11 of the bed plate 10. The shaft carries a driving gear 40 adjacent its upper end, which gear is in mesh with a first seaming station driving pinion 41 and a second seaming station driving pinion 42.

As more clearly shown in Fig. 3 of the drawings, the pinion 41 is mounted upon a sleeve 43 and a spindle 43' which spindle is carried by the bearing 44 which is formed as a part of the cantilever bracket structure 38. The sleeve 43 is mounted upon the spindle 43' which extends downwardly and is provided with a rotary seaming head 45 of the general type shown in Patent No. 1,611,523, issued to me December 21, 1926.

The seaming head is here shown comprising a cage 46 which is secured to the lower end of the sleeve 43 and which is provided at its opposite sides with slotted openings into which the levers 47 of the first seaming operation 48 are mounted. These levers are carried on pivots 49 so that the levers may swing readily in a vertical plane upon diametrically opposite sides of the axis of the sleeve 43. The lower ends of the levers carry the seaming rollers 48. The upper ends of the levers carry operating cam rollers 50. The cam rollers are disposed in bearing relation to a frusto-conical cam 51 which is slidably mounted upon the sleeve 43. A yoke 52 is mounted in a groove formed circumferentially of the upper end of the cam 51 and is provided with trunnions 53 at its opposite sides. These trunnions are engaged by the arms of a shifting fork 54 which fork is pivotally mounted upon a pin 55 to permit it to swing vertically. Upon the opposite side of the pivot from the fork 54 and formed integral with said fork, is a shifting arm 56 which extends into the column 14 and carries a roller 57 at its free end. This roller rides in the circumferential groove 58 of a cam 59, which cam is keyed to a cam shaft 60 extending longitudinally of and within the column 14. The upper end of cam shaft 60 extends through a vertical bearing 61 in the bearing structure 15 and receives a mitre driving gear 62 which is in mesh with a pinion 63 carried upon the mandrel 18 and keyed thereto.

Referring again to the structure of the first seaming head 45, it will be seen that the lower end of the cage 46 is cylindrical in shape and that it provides a bell 64 into which a can and its associated cap are lifted prior to the seaming operation, and within which the can cap is brought to register with a circular clutch plate 65 secured to the lower end of the spindle 43'.

Disposed at a suitable distance from the mouth of the bell 64 is a horizontal floor 66 onto which cans may be moved by a can feed

and timing mechanism generally indicated at 67 in Fig. 1 of the drawings, and which will be hereinafter described.

An opening 68 is formed in the floor 66 and accommodates a lower chuck plate 69, the upper face of which normally lies flush and in the same horizontal plane with the face of the floor 66. This chuck plate is carried upon a lower chuck spindle 70. The spindle 70 is in longitudinal vertical alignment with the upper spindle 43' and is carried in bearings 71 and 72 within the bed plate. It will thus be understood that after a can has been brought to register with the opening 68 it will assume a seated position upon the lower chuck plate 69 after which the plate with the lower spindle 70 will rise vertically to project the upper end of the can and its associated cap into the mouth of the bell 64 and with the upper chuck plate 65 in register with and bearing against the cap and in which position the can will be stationary during the first seaming operation.

The lower spindle 70 is lifted by a vertically swinging arm 73 which is secured to a lift shaft 74 mounted upon a horizontal axis in bearings 75 and 76 of the bed plate. A collar 77 is disposed upon the spindle 70 and is provided with a circumferential groove 78 to receive a pin 79 which is carried by the lever 73. A helical spring 80 circumscribes the spindle 70 and rests upon the upper face of the shifting collar. A collar 81 is fixed upon the shaft 70 and suitably spaced so that when the shifting lever 73 swings upwardly it will exert pressure through the shifting collar 78 to the spring 80 and this in turn will engage the shaft collar 81 on the spindle 70 and cause the shaft to be lifted. Suitable adjustment may be made so that a can and cap will be held against the upper chuck plate 65 by the yielding pressure of the spring 80. The lever 73 is actuated by a cam arm 82 formed integral therewith and disposed upon the opposite side of the shaft 74. This arm carries a cam roller 83 engaging a groove 84 in a face cam 85. The face cam is fixed upon a jack shaft 86 disposed parallel to the shaft 74 and mounted upon suitable horizontally aligned bearings within the bed plate 10. The shaft 86 is driven from the cam shaft 60 by bevel gears 87 and 88 mounted upon shafts 60 and 86 respectively. The can with its partially formed seam is thereafter moved from the first seaming station as represented by its position between the chuck plates 65 and 69 to a second and final seaming station as represented by its position in longitudinal alignment with an upper rotating spindle 89 and a lower rotating spindle 90 which define the second seaming station, attention being directed to the fact that the first operation spindles 43' and 70 are non-rotatable, firmly holding the can in a fixed position during the preliminary seaming op-

120
125
130

eration while the spindles 89 and 90 are rotatable and spin the can at a high speed during the final seaming operation. The transfer of the can from the first seaming to the second seaming station is effected by a transfer star wheel 91 carried upon the upper end of a shaft 92. This shaft extends vertically through an upper bearing 93 and a lower bearing 94 in the bed plate 10. The star wheel is provided with semicircular pockets 95 in spaced equal distance to each other along the circumference of the star wheel, which pockets are swung on a radius to insure that the can will snugly seat within the pocket and will be carried in its set position from one seaming station to the other. The star wheel 91 is shown in Fig. 3 of the drawings as being disposed near the upper end of a can, but it will be understood that this star wheel may be suitably positioned vertically so as to insure that the can will be properly fed and accurately brought to register with the mechanism at the seaming stations. The lower end of the star wheel shaft 92 carries a timing disc 96 which is engaged at equal intervals by rollers 97 of timing arms 98. These arms are carried upon a subshaft 99 vertically mounted in bearings 100 and 101 of the bed plate and being driven from the cam shaft 60 through a pinion 102 thereon in mesh with the gear 103 on the shaft 99. The disc 96 and the arms 98 with their rollers 97 constitute a Geneva movement which insures that the star wheel 91 will intermittently rotate in synchronism with the other moving parts of the machine.

When a can has been moved to the second seaming station by the star wheel 91 it will be disposed upon a chuck plate 104. This chuck plate is mounted upon the upper end of the lower second operation spindle 90. The lower spindle 90 is rotatably mounted and vertically reciprocable in bearings 105 and 106. The spindle 90 carries a pinion 107 which is in mesh with a gear 108 secured to the lower end of seaming shaft 35. The lower second operation spindle 90 is vertically reciprocated by an arm 109 keyed upon rock shaft 74 and having a pin 110 at its outer end engaging a groove in collar 111. Attention is directed to the fact that in Fig. 3 of the drawings it is shown that collar 111 on the second operation spindle 90 and collar 78 on the first operation spindle 70 are tied together by a casting 112 so that the two shafts will reciprocate in unison. Stop collars 113 and 114 are secured upon the second operation spindle 90 and upon opposite sides of the shifting collar 111. The spindle 89 of the second operation station is in vertical alignment with the spindle 90 and is disposed thereabove. This spindle is carried in bearings 115 and 116, and is driven by a gear 42 keyed thereupon and in mesh with the driving gear 40. Mounted upon the lower

end of the spindle 89 is an upper chuck plate 117 against which the cap of a can is lifted and held during the action of the second operation seaming mechanism 118.

The second operation seaming mechanism 70 comprises a seaming roll 119 carried by a lever 120. This lever is disposed in a horizontal plane and is pivotally mounted upon a vertical pin 121. The lever thus swings radially toward and away from the periphery 75 of the chuck plate 117, and may exert pressure upon the seam initially formed between the can and its cap to finish the seam and to curl it in and flatten it. The lever 120 is formed integral with an operating lever 122 80 which is engaged by an eye bolt 123 pivotally secured at the end thereof by a pin 124. The eye bolt is provided with spacing collars 125 and 126 held in position by adjusting nuts 127. Disposed between the spacing collars is 85 a shifting collar 128 carrying trunnions 129. These trunnions are engaged by a horizontally swinging lever 130 mounted upon shaft 131. This shaft is vertically mounted and is rotated by a cam arm 132 carrying a roller 133 90 at its outer end. This roller projects an eccentric cam groove 134 on a face cam 135 which cam is secured to and rotates with the cam shaft 60.

At the first operation station it is often 95 necessary to insure that the can is loosened from the upper chuck plate after the first seaming operation has taken place. This is accomplished by a stripper rod 136 which extends downwardly through the upper spindle 43 and may be caused to project through the bottom face of the upper chuck disc 65 to force the cap of the can downwardly and to release it from a binding position around the chuck plate. This rod is reciprocably 100 operated by a pressure arm 137 which rests upon the head of the rod and moves it downwardly against the expansive action of a spring 138. The pressure arm is mounted upon a rock shaft 139 and is formed with a 105 continuing lever 140 carrying a roller 141 which engages the groove 142 of a cam 143. This cam is secured to the cam shaft 60 adjacent its upper end.

In operation of the present invention cans 115 are fed into the machine by suitable timing and feed means, as generally indicated at 144 in Fig. 1 of the drawings. This mechanism will not be described in detail in the present case since it forms the subject matter of a copending application entitled "Accelerating can feed," filed under date of June 15, 1928, Serial No. 285,663. This structure, however, comprises a plurality of feed arms 145 by which cans are fed onto a horizontally 110 moving feed chain 146. Feed fingers 147 are carried by the chain and project upwardly from the upper flight thereof to engage cans marked "A" in the drawings. The open cans are thus fed to the machine and there receive 115 120 125 130 135 140 145 150

caps "B" from a stack 148. The caps are fed to the cans by a cap feed mechanism generally indicated at 149 and which mechanism forms the subject matter of a copending application filed by me concurrently with the present case on August 4, 1928, Serial No. 297,569. This cap mechanism operates at right angles to the path of travel of the can and causes caps to be fed along guide rails 150 and 151 to a seated position over the mouth of the can, after which the can and its cap will be moved upwardly through a centering ring as indicated by numeral 152 in Fig. 3 of the drawings, and will thereafter be lifted into the bell 64 of the first seaming head 45. It will be understood that all of the parts of the mechanism will operate in synchronism and that a rounding member 153, as shown in Fig. 3 of the drawings, will act to securely set the incoming can within the pocket 95 of the transfer star wheel 91. When in this position the driving mandrel 18 will act through pinion 63 to drive the gear 62 and the cam shaft 60. This shaft will in turn impart rotation to a horizontally disposed shaft 86 through pinions 87 and 88. The lifting cam 85 will thus rotate, and due to the formation of the cam groove 84 in the face thereof, will act through pin 88 and lever 82 to rotate the rock shaft 74 and thus simultaneously lift the levers 73 and 109. This will act to simultaneously raise both of the lower seaming station spindles 70 and 90, and will cause the spindle 70 to raise its lower chuck 69 upon which the can is being seated prior to receiving its first seaming operation. The can will thus be moved vertically as guided by the arcuate recess 95 in the star wheel 91 and the rounding member 153 partially encompassing the outer side of the can. The can thus being moved upwardly through the centering ring 52 where it will receive the cap and will carry the cap into the mouth of the bell 64 and into register with the upper chuck plate 65. While the can and cap are thus being securely gripped between the upper and lower chuck plates 65 and 69, respectively, under a pressure arm by the tension of the spring 80, the upper seaming head will be in constant rotation with its seaming rolls 48 in their outermost positions. As the cam shaft 60 rotates its first seaming operation cam 59 will act upon the lever 56 to swing the lever 54 downwardly and to force the cone 51 between the pressure rolls 50 of the seaming roll levels 47. This will cause the seaming rolls 48 to simultaneously swing inwardly at diametrically opposite sides of the same area of the can and will cause the marginal edges of the can and cap to be curled over each other in a manner to perform the initial step in forming a lock seam. The cone 51 will move downwardly until the desired seaming operation has been completed by the rolls 48, after which the cam 59 will

cause it to recede and will permit the can to be released. Simultaneously with this movement and in proper timed relation thereto, the lifting cam 85 will rotate to relieve pressure upon the levers 73 and 109, 70 thus causing spindles 70 and 90 to be lowered.

As the chuck plate 69 recedes it will relieve pressure from the can which has been partially seamed, and if the seam of the can 75 does not bind the upper chuck plate 65, the can will move downwardly with the receding chuck 69. In the event that it does bind, however, the stripper rod 136 will be actuated by the cam 142 and the pressure arm 80 137, to force the rod downwardly and to loosen the can from the chuck.

At this time the shaft 99 will be constantly rotating and one of its operating arms 98 will engage a groove in the Geneva cam disc 85 96 to cause intermittent partial rotation of the star wheel shaft 92 and the star wheel 91. This rotation will be sufficient to move the partially seamed can from the first seaming station to a position at rest upon the lower 90 chuck plate 104 carried by the spindle 90 of the second seaming station. The cam 85 will then act through the levers 73 and 109 to again lift the lower spindles 70 and 90 and this will move the can and its associated 95 cap into contact with the upper chuck 117. The chucks 104 and 117 will thus be in simultaneous rotation and will cause the can to spin. During this operation cam shaft 60 will rotate the horizontally disposed cam 135 100 to cause it to swing the pressure lever 132, which in turn will swing lever 130 in a horizontal plane and will act through the eye bolt 123 to swing the lever arm 122 and the cam arm 120. This will cause the same finishing 105 roll 119 to press against the partially formed seam as the can spins and to thus finish the seam.

After the second seaming operation has been completed the seaming roller 119 will 110 move to its inoperative position and the chuck 104 will be lowered so that the can may be lowered from the seaming position, and may thereafter be carried from the machine by suitable means.

It will thus be seen that the double seaming machine here disclosed is decidedly simple in its construction, direct in its operation, and embodied in a machine of small compass and that it will rapidly and effectively form a tight seam between a can and its cap.

While I have shown the preferred form of my invention as now known to me, it will be understood that various changes might be made in the combination, construction and arrangement of all parts without departing from the spirit of the invention as claimed.

Having thus described my invention, what 130

I claim and desire to secure by Letters Patent is:

- 5 1. A double seaming machine of the intermittent type comprising a first seaming station and a second seaming station, complimentary chucks between which a can and cap are disposed at the first station and by which said can and cap are held in assembled relation to each other without axial rotation, a rotary seaming head at said first seaming station having rollers adapted to move around the perimeter of the can and cap to form the initial seam, can transfer means 10 for moving the can and its cap from the first to the second seaming station, a pair of chuck members between which the assembled can and cap are positioned by said transfer means, means for driving said members to axially rotate the can and seaming means 15 adapted to exert pressure against the partially formed seam to complete the seam.
2. In a double seaming machine a second seaming station comprising a lower chuck plate onto which a first seaming station, a second seaming station, partially seamed can and cap may be disposed, an upper chuck plate cooperating therewith to clamp a can and cap therebetween, means for lifting the lower chuck to produce said clamping action, 25 means for simultaneously rotating the two chucks and the can and cap clamped therebetween, and seaming means automatically operating to move toward and then away from the partially formed seam of the can and cap to exert pressure thereagainst and clamp the same while they are rotating.
3. A double seaming machine comprising first and second seaming stations, the first seaming station including a lower chuck plate onto which a can and its associated cap may 30 be delivered, an upper chuck plate, means for raising the lower chuck plate to lift the can and cap until they are in clamped relation between the two chuck plates, seaming rollers adapted to move around the can and cap, means for driving said seaming rollers and automatically operating means for causing said rollers to swing inwardly to curl the flange at the upper edge of the can and the edge of the cap to form a lock seam and thereafter acting to permit the rollers to move to inoperative positions, transfer means for moving said partially seamed can and cap from the first station to the second station 45 said second station comprising a lower chuck plate onto which a partially seamed can and cap may be disposed, an upper chuck plate cooperating therewith to clamp a can and cap therebetween, means for lifting the lower 50 chuck to produce said clamping action, means for simultaneously rotating the two chucks and the can and cap clamped therebetween, and seaming means automatically operating to move toward and then away from the partially formed seam of the can and cap to 55

exert pressure thereagainst and clamp the same while they are rotating.

6. In a double seaming machine comprising a chuck onto which a can may be disposed, a vertical spindle disposed beneath and carrying said chuck, bearings through which said spindle may reciprocate, a shifting lever by which said spindle may be reciprocated and a timing cam for oscillating said shifting lever, a complimentary upper chuck member towards which the lower chuck member moves when thus shifted to clamp a can and associated cap therebetween, an upper spindle carrying said upper chuck, seaming means mounted to rotate therearound to form a lock seam between the can and cap, vertically reciprocating means mounted on said spindle for moving the seaming means toward and away from the cap, means for constantly driving said seaming means, and drive means acting in synchronism to actuate the lower spindle shifting lever and the upper spindle seaming means operating member to first lift the can and cap into clamped relation to the upper and lower chucks and to thereafter move the seaming means into operative relation to the perimeter of the cap, a stripper rod vertically reciprocating through the upper spindle to loosen the cap from the upper chuck after the initial seaming operation, and means for causing said stripper rod to be actuated in synchronism with and following the operative actuation of the seaming means.
7. In a double seaming machine, a driving member, a driven member, a first and second seaming station in geared relation to 120

- 130

said driven member, a vertically reciprocable spindle in medial vertical alignment with the first of said seaming stations, automatic means operating in synchronism with the whole, to vertically reciprocate said spindle, to engage and to release a can and its cap, resilient means to permit yieldable vertical movement in said spindle, a cone 5
slidable in timed relation with the whole to cause the seaming rollers to engage the work, a cam to actuate a star wheel to transfer the work to the second station, a second spindle, means employing said first spindle lifting organization to vertically reciprocate 10
said second spindle to cause a can and cap to be engaged and then to move from said second seaming station, means in timed relation with the whole to cause said second seaming station rollers to engage and then move from the work, and means in timed relation with 15
the whole to forcibly remove cans from said first seaming station.
